UNITED STATES PATENT OFFICE.

CHARLIE A. POST, OF KANSAS CITY, MISSOURI.

DESIGN FOR A KITCHEN-CABINET.

SPECIFICATION forming part of Design No. 32,888, dated June 26, 1900.

Application filed May 25, 1900. Serial No. 18,010. Term of patent 7 years.

To all whom it may concern:

Be it known that I, CHARLIE A. POST, a citizen of the United States, residing at Kansas City, in the county of Jackson and State of Missouri, have invented and produced a new and original Design for Kitchen-Cabinets, of which the following is a specification.

My invention relates to kitchen-cabinets; and my object is to produce a new and useful 10 design for the same.

Referring to the accompanying drawing, which represents a perspective view of a kitchen-cabinet embodying my design, it will be noticed that the leading or material feature 15 of the same consists in its novel and peculiar configuration, the base or lower portion being of rectangular form and the body or upper portion of cylindrical form, with the representation of a door near the lower end of the 20 upper or body portion.

Minor features of my design reside in a series of can-like figures projecting forward from the body or upper portion and arranged in a vertical column above said door-like figure; also, in the door-like figure of the base 25 portion, in the representation of cylindrical cup-brackets at opposite sides of the door-like figure of the upper or body portion, in the cylindrical can-like figures apparently seated 30 in said cup-like brackets, in the flat or rectangular cup-like figures on the upper or body portion at opposite sides of the vertical series

of can-like figures and above the can-like figures seated apparently in said cup-brackets; also, in the conical top or cover, and in the 35 handle-like figures at the upper end of the upper or body portion.

In detail, 1 designates the rectangular base, provided with the door-like figure 2.

3 designates the cylindrical upper or body 40 portion; 4, the door-like figure at the lower end of the same; 5, the vertical series of can-like figures, projecting forwardly from the upper or body portion; 6, the cup-brackets at opposite sides of the door-like figure 5; 7, the 45 cylindrical can-like figures, apparently seated in said cup-like brackets; 8, the rectangular cup-like figures on the upper or body portion at opposite sides of the vertical series of can-like figures; 9, the conical cap or cover, and 50 10 the handle-like figures of the top or body portion.

Having described the invention, what I claim as new, and desire to secure by Letters Patent, is—

The design for a kitchen-cabinet as herein 55 shown and described.

In testimony whereof I affix my signature in the presence of two witnesses.

CHARLIE A. POST.
